UNITED STATES PATENT OFFICE.

CORRY B. COMSTOCK, OF NEW YORK, N. Y.

FLOOR-DRAIN.

1,143,174.

Specification of Letters Patent. Patented June 15, 1915.

Application filed February 25, 1913. Serial No. 750,658.

To all whom it may concern:

Be it known that I, CORRY B. COMSTOCK, a citizen of the United States, residing at New York, in the county of New York and 5 State of New York, have invented certain new and useful Improvements in Floor-Drains, of which the following is a specification, reference being had therein to the accompanying drawing.

10 This invention relates to improvements in floor drains of the type adapted to be embedded in a floor of concrete or similar material and to receive and conduct away surface water.

15 The object of the invention is to provide a drain so constructed that it is impossible for water to leak around it to points outside of the discharge pipe. When such leakage occurs, damp places are formed in 20 and beneath the floor, and the accumulation of water may result in disagreeable and unsanitary conditions. With a drain embodying my invention such results are entirely prevented.

25 With the foregoing and other objects in mind, my invention consists of the improved constructions and arrangements of parts set forth in the following specification and shown in the drawing. It will be understood, however, that various changes and 30 modifications may be made within the scope of the appended claims without departing from the spirit of my invention.

Of the drawing—Figure 1 is a vertical cross sectional view taken through a floor drain embodying my invention. Fig. 2 is a similar view showing a modified form of 35 floor drain embodying my invention.

Referring to Fig. 1 of the drawing, 1 represents a bowl, preferably conical in shape, adapted to be set into a suitable opening or depression in a floor. 2 is a cover for the bowl 1, and this cover is perforated to permit water or other liquids to pass through 40 into the bowl. In the drawing I have shown a flat cover, but it will be understood that this can be made convex or concave when desired. The lower end of the bowl 1 is provided with a downward extending 45 pipe or duct 3. The duct 3 fits loosely within another larger duct 4, at the upper end of which there is formed an upward and outward extending conical flange 5 which forms a bowl surrounding the bowl 1, but 50 terminating at its upper edge below the level of the upper part of the bowl 1 and

the cover 2. Preferably, a ledge or series of lugs 5' is provided at the lower part of the bowl 5 for engaging with and supporting the inner bowl 1 and the duct 3. This is 55 provided at intervals with openings or recesses to permit the passage of liquid.

The tube or duct 4 can communicate with the discharge pipe in any usual or preferred manner. As shown in the drawing, the duct 4 extends into the enlarged upper end of a pipe 6, which is made S-shape in form to provide a trap. However, as to the pipe 6 and its connection with the tube or duct 4, there can be wide variation.

When the drain is in place in a floor, the outer bowl 5 is embedded in the body of the concrete or other material 7, of which the floor is formed. The bowl 5 is placed with its upper edge considerably below the top surface of the completed floor. The floor-forming material extends upward over the top edge of the bowl 5 and downward within it, completely filling the upper part of the space between the two bowls 5 and 1. 70

The inner bowl 1 is placed with its top edge flush with the floor surface. In the drawing I have shown a floor formed of two different materials, one being a body or foundation of grout or concrete, and the other being a surface layer, which can be formed of asphalt or waterproof cement. The upper surface layer is indicated in the drawing by 8. Preferably, the division line between 75

the two parts of the floor is on a level with the top of the bowl 5, the surface-forming layer alone extending into the space between the two bowls. It will be understood, however, that my improved drain is not limited in its use with a floor formed of two materials. It will be obvious that it is equally useful with a floor formed of one material 80 throughout.

It will be observed that the adjacent lower parts of the two bowls converge near 100 the spaces or apertures between the lugs at 5', 5''. This converging of the walls serves to retard the movement of the floor material into the space and to prevent its entering the apertures to clog them.

105 The operation and advantages of my improved construction will now be readily apparent. The greater part of the water or other liquid which reaches the floor flows into the drain through the apertures in the 110 cover plate 2. But it has been found practically impossible to make an absolutely

2

tight connection between the bowl 1 and the floor body. Consequently, it usually happens that a certain amount of water finds its way down along the outer surface 5 of the bowl between it and the body of the floor material. In drains, as heretofore constructed, this liquid thus flowing down outside of the bowl has been lost and has been permitted to collect beneath the floor or to flow downward along the outside of the discharge pipe. To prevent this, I have provided the supplemental bowl 5 outside of the bowl 1 which serves to collect this liquid and guide it into the discharge pipe. 15 It will be clear from the drawing that the liquid can flow down along the outside of the bowl 1 and through the space between the outer surface of the duct 3 and the inner surface of the duct 4. As an additional 20 precaution, I prefer to provide a series of holes 9, 9, in the duct 3 through which the liquid can flow in case the space before referred to between the ducts 3 and 4 should become clogged. These apertures when 25 used are preferably placed opposite the recesses in the shelf 5.

In Fig. 2 I have shown a modified form of floor drain embodying my invention. A detailed description of this will not be necessary as it is similar in most respects to the construction shown in Fig. 1. It will be noted, however, that there is an inner bowl 1^a, a cover plate 2^a, an outer bowl 5^a, and a discharge tube 4^a communicating with 30 a discharge pipe 6^a. The construction differs principally from that shown in Fig. 1 in that the bowl 1^a is formed integrally with the bowl 5^a and the duct 4^a. In this case 35 apertures at 9^a are essential for admitting to the interior of the duct 4^a the liquid which finds its way downward along the outside of the bowl 1^a.

It will be observed that by my invention I have provided a floor drain having two 45 concentric bowls each adapted to be completely embedded in the floor; and I have so combined these bowls with the floor that each is entirely surrounded from top to bottom by the floor material. In the preferred embodiment of the invention the floor is formed in two layers and the outer bowl is made flush at its top with the top surface 50 of the lower layer and the inner bowl is made flush at its top with the top surface of the upper layer, the upper layer preferably extending downward into the space between the two bowls. As stated above, the top layer of the floor is formed of a material adapted to resist the passage of water, the result being that any seepage of water around the drain outside of the outer bowl 5 is prevented.

In constructing the floor and placing the drain it will be seen that the lower layer 55 of the floor can be put in place first and

made level with the top of the drain. While this is being done the inner bowl can be removed so as not to interfere with the construction of the lower floor layer. Later, when the workmen are ready to lay the 70 top layer of the floor the inner bowl 1 is set in place on the outer bowl and the top layer 8 of the floor is spread and made level with the top of the inner bowl. As before stated, the two bowls are so constructed that 75 their walls converge near the bottoms so as to prevent the plastic material of which the top layer of the floor is formed from flowing down to choke the apertures.

Each of the bowls is provided with an 80 inner surface which is substantially unobstructed and which is sharply inclined downward and inward. This smooth, unobstructed, sharply inclined surface is very important, especially for the outer bowl, as 85 it is necessary for any fluid that may reach the said inner surface to flow freely down it to the discharge outlet. This inner surface is necessarily greatly obstructed by the floor material and the liquid at best can 90 flow only through the pores and interstices of the material. It is, therefore, essential that the path for the liquid be left otherwise free so that the liquid can follow freely the said pores and interstices of the 95 floor material.

What I claim is:

1. The combination of two concentric bowls having closely adjacent but separated imperforate walls sharply downward and inward inclined throughout, the outer of which has an unobstructed inner surface and extends upward a considerable distance above the bottom plane of the inner and terminates a considerable distance below the top plane of the inner, and means for receiving and discharging liquid from the interiors of both bowls.

2. The combination of two concentric bowls having closely adjacent but separated imperforate walls sharply downward and inward inclined throughout, the outer of which has an unobstructed inner surface and extends upward a considerable distance above the bottom plane of the inner and terminates a considerable distance below the top plane of the inner, a discharge duct with which the inner bowl communicates, and connecting means between the inner and the outer bowls having apertures the lower surfaces of which are inclined and in register with the inclined inner surface of the outer bowl.

3. The combination of two concentric bowls, a discharge duct with which the inner bowl communicates, and connecting means between the inner and the outer bowls having apertures, the said bowls having closely adjacent but separated imperforate walls sharply downward and inward inclined throughout, the outer of which has an unobstructed inner

surface and extends upward a considerable distance above the bottom plane of the inner and terminates a considerable distance below the top plane of the inner, the adjacent parts of the said walls converging near the said apertures.

4. The combination of two separable concentric bowls having closely adjacent but separated imperforate walls sharply downward and inward inclined throughout, the outer of which has an unobstructed inner surface and extends upward a considerable distance above the bottom plane of the inner and terminates a considerable distance below the top plane of the inner, means for supporting one of the bowls on the other in definite predetermined relation thereto, and means for receiving and discharging liquid from the interiors of both bowls.
5. The combination of two separable concentric bowls having closely adjacent but separated imperforate walls sharply downward and inward inclined throughout, the outer of which has an unobstructed inner surface and extends upward a considerable distance above the bottom plane of the inner and terminates a considerable distance below the top plane of the inner, means comprising a series of spaced lugs for supporting the inner bowl on the outer, and a duct for receiving and discharging liquid from the interior of the outer bowl and positioned to also receive and discharge liquid from the interior of the inner bowl.
6. The combination of two separable concentric bowls having closely adjacent but separated imperforate walls sharply downward and inward inclined throughout, the outer of which has an unobstructed inner surface and extends upward a considerable distance above the bottom plane of the inner and terminates a considerable distance below the top plane of the inner, means for supporting the inner bowl on the outer, a duct for receiving and discharging liquid from the interior of the outer bowl, and a tube connected with the inner bowl and extending downward into the duct.
7. The combination of two separate concentric bowls having closely adjacent but separated imperforate walls sharply downward and inward inclined throughout, the outer of which has an unobstructed inner surface and extends upward a considerable distance above the bottom plane of the inner and terminates a considerable distance below the top plane of the inner, means comprising a series of spaced lugs for supporting the inner bowl on the outer, a duct for receiving and discharging liquid from the

interior of the outer bowl, and a tube connected with the inner bowl and extending downward into the duct, the walls of the said tube having apertures therein opposite the spaces between the said lugs.

65

8. The combination of a floor, two concentric bowls each embedded in the floor from top to bottom and having closely adjacent but separated sharply downward and inward inclined imperforate walls, the inner of which is flush at its top with the top surface of the floor and the outer of which terminates at its top a considerable distance below the top surface of the floor, and means for receiving and discharging liquid from the interior of both bowls.

9. The combination of two concentric bowls having closely adjacent but separated imperforate walls sharply downward and inward inclined throughout, the outer of which has an unobstructed inner surface and extends upward a considerable distance above the bottom plane of the inner and terminates a considerable distance below the top plane of the inner, and a floor in which the two bowls are completely embedded from top to bottom, the said floor being formed of two horizontal layers of differing materials, the lower layer being flush at its top surface with the top of the outer bowl and the upper layer of the floor being flush at its top surface with the top of the inner bowl and extending downward into the space between the two bowls.

10. The combination of two concentric bowls separable at points near their bottoms and having closely adjacent but separated imperforate walls sharply downward and inward inclined throughout, the outer of which has an unobstructed inner surface and extends upward a considerable distance above the bottom plane of the inner and terminates a considerable distance below the top plane of the inner, and a floor in which the two bowls are completely embedded from top to bottom, the said floor being formed of two horizontal layers of differing materials, the lower layer being flush at its top surface with the top of the outer bowl and the upper layer of the floor being flush at its top surface with the top of the inner bowl and extending downward into the space between the two bowls.

In testimony whereof I affix my signature, in presence of two witnesses.
